UNITED STATES PATENT OFFICE.

WILLIAM C. BEACH, OF BLOOMFIELD, NEW JERSEY, ASSIGNOR TO WESTERN ELECTRIC COMPANY, INCORPORATED, OF NEW YORK, N. Y., A CORPORATION OF NEW YORK.

CONTROL SYSTEM FOR PRODUCING SIGNALS OF VARIOUS FREQUENCIES.

Application filed August 18, 1924. Serial No. 732,673.

This invention relates to a signaling system for use in automatic telephone systems.

It is an object of this invention to provide an improved signaling system.

In telephone exchange systems, particularly of the automatically operated type, a large variety of signals is required and various tones, such as dial tone, busy tone, etc., are used to acquaint the subscriber with conditions that are encountered during the operation of central office apparatus for service connections. It is important that a tone used for any given purpose be of the same frequency and pitch in all circuits, and to obtain this same tone under various conditions, an adjustable tone producing circuit is an essential improvement.

The utility of a control system for producing signals of various frequencies is great since a standard apparatus combination may be used in various types of circuits associated with subscriber's or operators' apparatus for many purposes. It is well known that any part of a system that is standardized affords economy.

A feature of this invention relates to the use of an improved electrical control system for producing signals of various frequencies.

This and other features of the invention will be apparent from the following description, taken in connection with accompanying drawing.

While the invention has been disclosed as particularly adapted for signals in an automatically operated telephone system, it will be apparent from the following description that the invention has a wider utility and that by slight modification, it may be adapted for use with other types of apparatus in which an adjustable signaling system is required.

Fig. 1 of the drawing illustrates the preferred form of apparatus for transmitting a tone through a receiver, including adjustable apparatus for changing the frequency and pitch of the tone. Figs. 2, 3 and 4 illustrate alternative forms of the same structure, in which Figs. 2 and 3 show apparatus for transmitting a tone inductively to a receiver and Fig. 4 shows apparatus for flashing a lamp.

Let it be assumed that it is desirable to transmit a tone of a given frequency and pitch through receiver 5. Fig. 1. The operation of key 1 establishes a circuit from grounded battery through the winding and

contact of relay 6, variable resistance 3 to ground through the contact of key 1. Upon the operation of relay 6, its operating circuit is opened at its contact. At this time, condenser 2 is charged from grounded battery through the winding of relay 6. This charging current maintains relay 6 in an operated position until the condenser is charged to a point where the current flow has diminished to the releasing adjustment of relay 6. The release of relay 6 reestablishes its operating circuit and establishes a discharge circuit for condenser 2 through resistance 3. The resistance 3 regulates the amount of current permitted to pass through the winding of relay 6 and also regulates the rate of discharge of condenser 2 thus controlling the duration of time that the relay contact is closed. When relay 6 is caused to be released by the potential increase of condenser 2, the condenser immediately starts to discharge at a rate permitted by resistance 3. Until such time as the potential of condenser 3 has been materially reduced the operating circuit for relay 6 is not effective since the condenser charge acts as a shunt to prevent the operation of the relay. As the potential of the condenser charge decreases, the current through the winding of relay 6 increases until the current is strong enough to cause the relay to attract its armature. The foregoing operating sequence continues until key 1 is released. The duration of time that relay 6 is held in an operated position is dependent upon the capacity of condenser 2. The continued operation and release of relay 6 produces a tone which is transmitted through condenser 4 and receiver 5. Condenser 4 is of such capacity that the releasing time constant of relay 6 is not materially affected thereby.

Condenser 2 and resistance 3 may be varied to control the operating and releasing time constants of relay 6. By controlling the time constants of relay 6 the frequency of the tone source may be varied with ordinary apparatus from 15 to 1000 interruptions per second and thus the tone pitch may be widely varied. By using a specially designed relay in lieu of relay 6 these variations in tone can be made much greater.

The operator of the circuit of Fig. 2 is the same as for Fig. 1 with the exception that relay 7 has two windings inductively associated. A tone current as described for Fig. 1 is produced in the left winding of relay 7

and induced into the right winding for transmission through receiver 5.

The operation of the circuit of Fig. 3 is the same as that described for Fig. 1 with the exception that the operating circuit for relay 8 is carried through the left winding of inductive coil 9. The tone current produced in the left winding of coil 9 is transmitted by inductance to the right winding of coil 9 and thence through receiver 5.

The operation of relay 10, shown in Fig. 4, is the same as that described for relay 6 of Fig. 1. In this circuit combination, contact 11 is closed upon the operation of key 1. Relay 10 in its normal position establishes a circuit to light lamp 12 from ground through the right contact of said relay, contact 11, lamp 12 to grounded battery. Upon each operation of relay 10, lamp 12 is extinguished. The capacity of condenser 2 and the resistance of coil 3 may be changed to vary the frequency of flashing lamp 12.

While the contact used to establish an operating circuit for relays 6, 7, 8 and 10 is shown as a key, it will be apparent that this contact may be associated with a relay or other apparatus operated in combination with any electrical circuit. It is further apparent that any type of recording instrument may be used to record the interruptions.

What is claimed is:

1. A device for producing and controlling the frequency of electrical oscillations in an electrical circuit comprising an electromagnet having an armature, an energizing circuit for said electromagnet, a holding circuit including a capacity, and means for adjusting said capacity to determine the rate of release of said device and thereby controlling the frequency of the oscillations produced.

2. A device for producing electrical oscillations in an electrical circuit comprising an electromagnetic device having a winding, a condenser adapted to be connected in series with said winding and a source of potential, means to vary the rate of charging of said condenser during its connection to said source of potential and consequently the periodicity of said electromagnetic device, and a discharge path for said condenser independent of said device.

3. A device for producing and controlling the frequency of electrical oscillations in an electrical circuit comprising an electromagnet, an armature and contact, an energizing circuit for said magnet including said armature and contact, an independent holding circuit for said magnet including a condenser, and means to vary the capacity of said condenser to control the rate of release of said magnet.

4. A device for producing and controlling the frequency of electrical oscillations in an electrical circuit comprising an electromagnet having an armature, an energizing circuit

for said electromagnet including a resistance, a holding circuit including a condenser of variable capacity, means for adjusting said resistance to determine the time of energization of said device, and means for adjusting said capacity to determine the rate of release of said device and thereby controlling the frequency of the oscillations produced.

5. A device for producing electrical oscillations in an electrical circuit comprising an electromagnetic device having a winding, a condenser adapted to be connected in series with said winding and a source of potential, means for varying the rate of charging said condenser during its connection to said source of potential for controlling the periodicity of said electromagnetic device, and means to vary the rate of discharging said condenser for further controlling the periodicity of said electromagnetic device.

6. A device for producing and controlling the frequency of electrical oscillations in an electrical circuit comprising an electromagnet, a primary energizing circuit for said electromagnet including a resistance, a secondary circuit for said electromagnet including a condenser, means to progressively establish said primary and said secondary circuits for respectively energizing said electromagnet and for sustaining energy in said electromagnet for a time period depending on the capacity of said condenser, a discharge circuit for said condenser including said resistance arranged to retard the energization of said electromagnet, and means to adjust said resistance to regulate the periodicity of said device.

7. A device for producing and controlling the frequency of electrical oscillations in an electrical circuit comprising an electromagnet, a primary energizing circuit for said electromagnet including a resistance, a secondary circuit for said electromagnet including a condenser, means to progressively establish said primary and secondary circuits for respectively energizing said electromagnet and for sustaining energy in said electromagnet under the control of the potential increase in said condenser, a discharge circuit for said condenser including said resistance arranged to retard the energization of said electromagnet, means to adjust said condenser to regulate the possible potential increase, and means to adjust said resistance to regulate the rate of discharge of said condenser thereby controlling the frequency of oscillations produced.

8. A device for producing and controlling the frequency of electrical oscillations in an electrical circuit comprising an electromagnet, a primary energizing circuit for said electromagnet including a resistance, a condenser of variable capacity, a charging circuit for said condenser including said electromagnet for maintaining the energization

- of said electromagnet throughout the period of charging, a discharge circuit for said condenser arranged to retard the energization of said electromagnet over said primary circuit, means to adjust the capacity of said condenser to vary the period of sustained energization of said device, and means to adjust said resistance to vary the rate of discharge of said condenser for controlling the time of energizing said device.

9. A device for producing and controlling the frequency of electrical oscillations in an electrical system comprising an electromagnet, a primary energizing circuit for said electromagnet including a resistance, a condenser of variable capacity, a charging circuit for said condenser including said electromagnet for maintaining the energization of said electromagnet throughout the period of charging, a discharge circuit for said condenser arranged to retard the energization of said electromagnet over said primary circuit, means to adjust the capacity of said condenser to vary the period of sustained energization of said device, and means to adjust said resistance to compensate for various adjustments of said condenser to maintain a constant rate of discharge of said condenser for controlling the periodicity of said device.

20 10. A device for producing and controlling the frequency of electrical oscillations in an electrical circuit comprising an electromagnet having a normally closed contact, an energizing circuit for said electromagnet including a resistance, a holding circuit for said electromagnet including a condenser, means for establishing said circuits for opening and closing said contact, means for adjusting said resistance to control the closed period of said contact, and means to adjust the capacity of said condenser to control the open period of said contact.

25 11. A device for producing and controlling the frequency of the electrical oscillations in an electrical circuit comprising an electromagnet having a normally closed contact, a primary energizing circuit for said electromagnet including a resistance and said contact, a secondary circuit for said electromagnet including a variable condenser normally shunted by said resistance, means to establish said primary circuit for opening said contact thereby establishing said secondary circuit for sustaining energy in said electromagnet for a time period depending upon the capacity of said condenser, a discharge circuit for said condenser including said contact and resistance arranged to retard the energization of said electromagnet, and means to either adjust the resistance or the capacity of said condenser for controlling the periodicity of said device.

30 12. A device for producing and controlling the frequency of electrical oscillations in an electrical circuit comprising an electromagnet having a normally closed contact, a primary energizing circuit for said electromagnet including a resistance, a condenser of variable capacity, a charging circuit for said condenser including said electromagnet for maintaining the energization of said electromagnet throughout the period of charging, a discharge circuit for said condenser arranged to retard the energization of said electromagnet over said primary circuit, means to adjust the capacity of said condenser to vary the period of sustained energization of said device, and means to adjust said resistance to vary the rate of discharge of said condenser for controlling the periodicity of said device.

35 13. A device for producing and controlling the frequency of the electrical oscillations in an electrical circuit comprising an electromagnet having a normally closed contact, a primary energizing circuit for said electromagnet including a resistance and said contact, a secondary circuit for said electromagnet including a variable condenser normally shunted by said resistance, means to establish said primary circuit for opening said contact thereby establishing said secondary circuit for sustaining energy in said electromagnet for a time period depending upon the capacity of said condenser, a discharge circuit for said condenser including said contact and resistance arranged to retard the energization of said electromagnet, and means to either adjust the resistance or the capacity of said condenser for controlling the periodicity of said device.

40 14. A device for producing and controlling the frequency of electrical oscillations in an electrical circuit comprising an electromagnet having a normally closed contact associated with said electrical circuit, a primary energizing circuit for said electromagnet including said resistance and contact, a secondary circuit for said electromagnet including a condenser, means to progressively establish said primary and secondary circuits for respectively energizing said electromagnet for opening said contacts and for sustaining energy in said electromagnet for a time period depending upon the release adjustment of said electromagnet, a discharge circuit for said condenser including said resistance and contact arranged to retard the energization of said electromagnet, and means to adjust said resistance to regulate the rate of discharge of said condenser for controlling the periodicity of said contact movement.
